ATTY.

UNITED STATES PATENT OFFICE:

WILLIAM ELLERY, OF SAN FRANCISCO, CALIFORNIA.

DESIGN FOR A HUNTING-KNIFE.

49,263.

Specification for Design.

Patented June 27, 1916.

Application filed March 22, 1916. Serial No. 86,004. Term of patent 14 years.

To all whom it may concern:

Be it known that I, WILLIAM ELLERY, a citizen of the United States, residing at San Francisco, in the county of San Francisco and State of California, have invented a new, original, and ornamental Design for Hunting-Knives, of which the following is a specification, reference being had to

the accompanying drawing, forming part thereof.

The figure is a side view of a hunting knife, showing my new design.

I claim:—

The ornamental design for a hunting knife, as shown.

WILLIAM ELLERY.
